search Foundation, Chicago, Ill., a corporation
of Illinois

Application December 31, 1946, Serial No. 719,388

7 Claims. (Cl. 250—43)

1

This invention relates to the sterilization of liquid solutions or suspensions which are contaminated with micro-organisms without altering the chemical nature or impairing the biologic activity of substances in the solution. By means of the present invention we are able to produce sterile solutions or suspensions of delicate compounds which cannot be satisfactorily sterilized by the now commonly practiced methods of sterilization.

At present, the accepted methods of sterilization of solutions or suspensions are:

(1) Steam sterilization under pressure for twenty to thirty minutes, or dry heat sterilization at 180° C. for two hours.

(2) The addition of bactericidal chemicals.

(3) Filtration through filters of a selected porosity to remove certain types of micro-organisms.

None of the three methods is completely satisfactory for sterilizing liquids containing delicate substances. Heat will coagulate proteins or otherwise change unstable compounds. Chemicals may also adversely affect such delicate compounds. Upon standing chemicals will progressively act on delicate compounds and the potency or chemical activity of these compounds may be progressively weakened. Furthermore, the presence of these chemicals in the solutions is often dangerous and harmful if the solutions are to be used for humans. The filtration process has two disadvantages; first, filterable viruses will not be removed, and secondly, there is a loss of the active material by adsorption to the filter.

The present invention comprises a process whereby contaminated solutions or suspensions can be completely sterilized and all viruses inactivated without materially impairing the potency or changing the chemical activity of any delicate compounds contained in the solution. This result is accomplished by the irradiation of flowing thin films of such solutions or suspensions for a few seconds with rays emitted by an extreme-low-pressure mercury arc discharge. The lamp which we employ is described in the copending application of Franz Oppenheimer, Serial No. 581,405, filed March 7, 1945. This extreme-low-pressure arc discharge emits radiation in powerful intensities in the region between 1800 and 2600 Å.

Prior efforts to sterilize contaminated suspensions containing delicate compounds with ultraviolet light have not produced satisfactory results. In these attempts, so called cold quartz lamps or ordinary quartz mercury arcs were employed. Relatively long exposures, from several minutes to one hour, were necessary to completely sterilize such solutions. These long exposures necessarily heat up the solutions, and have a deleterious effect upon delicate substances.

The lamps used, such as the cold-quartz lamp or the hot-cathode mercury discharge lamp, do not

2

produce short ultra-violet radiation in great intensities. The lamp described in the copending application, Serial No. 581,405, produces radiation in the range from 1800 to 2600 Å., in intensities from 10 to 100 milliwatts per square centimeter. These measurements have been made by exposing one centimeter of the radiation tube at a distance of one centimeter from the lamp. Under similar conditions, lamps of the cold- or hot-cathode discharge type produce not more than one milliwatt of radiation, of which eighty-five percent is concentrated in the band designated as 2537 Å. None of the lamps heretofore used for sterilization has any appreciable amount of radiation below 2000 Å., while the lamp which we employ produces approximately twenty to thirty percent of its energy in the ultraviolet in radiation below 2000 Å.

The time necessary to sterilize contaminated suspensions or solutions with lamps previously known is so long that the resultant products are unsatisfactory. Many investigators concluded that, while it takes a certain amount of ultraviolet energy to sterilize bacteria and inactive viruses, the time in which this energy is given to the suspension of micro-organism is of little consequence. Our investigations have shown that there is a minimum amount of ultraviolet energy to which a solution containing a certain number of bacteria or viruses must be exposed in a certain time unit to render it sterile, and it is not possible to achieve the same result by irradiating these solutions with a like total amount of ultraviolet energy in a correspondingly longer time. It has been determined that a minimum of 5 to 10 milliwatt seconds per square centimeter of energy of the wavelength 2537 Å. is required to produce adequate killing of micro-organisms (Acceptance of ultraviolet lamps for disinfecting purposes, Journal of the American Medical Association, January 24, 1942, page 298).

The principles which govern the action of ultraviolet on micro-organisms for sterilization of liquids are as follows:

(1) A definite amount of ultraviolet energy per time unit is required to kill the infectious agent.

(2) Ultraviolet, especially in the Schuman range, below 2000 Å., is readily absorbed in clear aqueous solutions and has limited penetration, particularly in turbid fluids containing organic matter.

(3) The ultraviolet energy must reach and be absorbed by the infectious agent to exert a lethal effect.

(4) Over-irradiation rapidly destroys the potency and changes chemical structure of compounds.

Our invention provides the means for producing completely sterile solutions or suspensions containing delicate compounds with minimum denaturation by very rapid exposure of a thin film to

powerful ultraviolet energy. In practicing our invention we use a powerful source of ultraviolet, which, besides strong emission in the far ultraviolet, emits light in the Schuman range (below 2000 Å), by means of which sterilization and inactivation are accomplished very rapidly. While ultraviolet energy in the range of 2600 to 2000 Å is very bactericidal, this bactericidal effect is enormously increased if radiation of the Schuman range is utilized. Our experiments have shown that energy of equal intensity in the Schuman range is at least ten times more bactericidal than the energy in the far ultraviolet.

In the practice of our invention we preferably employ a specially designed ultraviolet permeable irradiation chamber to produce a rapidly flowing, uniform film of a preparation containing micro-organisms which can be made as thin as 0.1 mm. Previous methods have employed stationary layers of suspensions in dishes or a column of fluid through a straight or spiral tube, depending on turbulence to expose all parts of the suspension. The exposure of suspensions in dishes as described requires very long periods of time (fifteen to ninety minutes), so that it not only is commercially impractical because the quantity of liquids is very small, but there is so much over-exposure that a denaturing effect is produced on the proteins and organic substances in the solution. With the use of suspensions in tubes there were also very long exposures (fifteen minutes to four hours) and the method is unreliable and incapable of standardization, so that consistent sterilization is not possible and often the suspension is of no value due to the over-irradiation which occurred. Our combination of an ultraviolet light source of sufficient intensity and a thin, uniform, flowing film of the delicate organic solution enables us to sterilize the contaminating organisms with the least amount of energy required for such sterilization, thereby avoiding deteriorating effects from over-irradiation. This procedure can be standardized and is constant, reproducible and reliable. Furthermore, this combination of powerful ultraviolet and rapidly flowing suspension yields large quantities of liquids, sufficiently large for commercial production.

In the practice of our invention we expose a fast-flowing thin film to the radiation of an extreme-low-vapor-pressure mercury arc discharge. The output of this extreme-low-vapor-pressure arc can be measured by physical means such as photocells, bolometers, thermopiles and spectrographic arrangements. While these measurements are relatively accurate, we find that biologic means are much more sensitive to determine the output of this extreme low-pressure arc in the extreme ultraviolet and the Schuman range of the spectrum. We have therefore devised a standard test to measure the radiation of the lamp. A film 0.1 mm. thick, containing 1,000,000 *B. coli* suspended in physiological saline solution, is exposed to the radiation of the lamp for $\frac{1}{20}$ of a second. If all the *B. coli* are killed, we consider the lamp output adequate. In many instances we expose this suspension for only $\frac{1}{30}$ of a second, which is close to the threshold of sterilization power of a lamp, and the remaining count of living *B. coli* gives a good indication of the output of bactericidal radiation. If there are proteins in the solution or if spores are present, much longer exposures (several seconds) may be required.

The irradiation cell which we are utilizing in this standard test is described and claimed in our

copending application, Serial No. 544,098, filed July 8, 1944, now abandoned. In the test described, the extreme-low-pressure arc discharge is operated at an electric input of 500 watts. In the standard test the suspension containing 1,000,000,000 *B. coli* flows through the irradiation cell at a rate of approximately three liters per hour. Compared with methods of the prior art, this flow is actually many times greater than heretofore achieved, and the procedure of this invention can easily be standardized, is constant and reproducible, and is absolutely reliable.

The time required to sterilize or inactivate bacteria or viruses is determined by three factors, first, the resistance of the micro-organism to ultraviolet energy, which varies considerably with the type of organism to be sterilized or inactivated; second, the count or concentration of bacteria or viruses; and third, the turbidity of the suspension which is to be sterilized.

To cite a specific example, we have been able to render completely sterile human plasma which contained the agent or virus of infectious hepatitis. This is a very valuable procedure and of great importance to public health. Despite great care in the preparation of human plasma from selected donors, it is possible that this agent might remain in the finished product in spite of the required safety tests, which are inadequate to detect the virus. It is, therefore, good practice to use this invention for the sterilization of all human plasma or serum. As there are no simple means of discovering this virus in plasma, we have adopted a standard routine to sterilize all human plasma and serum to make certain that this agent is inactivated. Infectious hepatitis virus is not easily inactivated, and we prefer to expose plasma in a thin film, rapidly moving, for a period of one to two seconds.

In the accompanying drawings we have illustrated an organization of apparatus elements suitable for use in practicing the process, the figure being a side elevation.

In the drawings the lamp illustrated of the type disclosed in the said Oppenheimer pending application comprises a base portion 10 made of high grade optical quartz and having a thickness of substantially 0.5 mm. In a specific embodiment this leg 10 has an inside diameter of 1 cm. and a length of 16 cm. Section 10 of the lamp is connected to legs 11 which may be of commercial quartz and which are of an over-all length of about 15 cm. Each of these legs is provided with a water jacket 12 having an outlet 13 at its highest point and an inlet 14 at its lowest point. As shown, the water jacket is provided with an extension 15 covering a portion of a base of the lamp and just beyond the end of the water jacket the commercial quartz forming the leg 11 is joined to the high grade quartz forming the base 10 by a suitable seal 16. A pool of mercury 17 is arranged in a bulb or extension 18 which projects beyond the water jacket and which is preferably of a length of about 3 cm. The lamp is connected to terminals 19 of a supply circuit through a switch 20 and an adjustable resistance or reactance coil 21 arranged in series with it.

Plasma is placed in flask 25 and delivered at a constant rate in close proximity to the leg 10 of the lamp. In the illustration, the flask 25 is arranged at an elevation to permit controlled flow of the plasma by gravity. The mouth of the flask is closed by a rubber stopper 26. A tube 21 for the inlet of air passes through the stopper and has its end arranged above the level of the plasma

as indicated at 28. The end of the tube outside the flask is also arranged at an elevation and is filled with a packing 29 of cotton or other suitable material. An outlet tube 30 extends through the rubber stopper and is connected to a flexible connector 31, such as a piece of rubber tubing. The flow of the suspension is controlled by a member 32 which, as shown, may consist of a capillary glass tube having a restricted portion 33. Any other controlling means may be employed. The other end of this tube is connected to a suitable connector 34 shown as rubber tubing, which is in turn connected to the cell 35 in which the radiation of the suspension takes place. The cell is also formed of high grade optical quartz readily permeable to wave lengths below 2000 Å. and consists of tubular end portions 36. The intermediate portion 37 of the cell is flattened forming a passage 38 through it of a thickness of about 0.1 mm. The thickness of the wall of the portion 37 of the cell facing the discharge must be very thin, not over 0.5 mm. The back portion of the cell is thicker to make the cell sturdy. We have obtained good results with a cell in which the flattened portion 37 is of a width of 1 cm. and a length of about 10 cm.

From the cell 35 the treated suspension is delivered to a sealed flask 39 in which it is collected. As shown, the flask is provided with a rubber stopper 40 having a tube 41 extending therethrough and the end of this tube is connected to the adjacent end of the cell by a suitable connector, such as a piece of rubber tubing 42. A second tube 43 extends through the stopper 40 and is provided with a packing 44 of cotton or other suitable material.

Batches of plasma tested in the apparatus and with the lamp above described for the inactivation of the agent of infectious hepatitis has been found to be completely safe and useful for intravenous administration after two seconds' exposure. Such irradiation has not resulted in any change of the proteins or decrease of other delicate substances, such as antibodies contained in plasma.

The present invention is very useful in the sterilization of products of biologic science and industry. Valuable products such as hormone suspensions (liver extract, insulin, adrenalin, pituitrin, thyroxine, etc.) can be sterilized in accordance with this invention without materially impairing their biologic properties. Human plasma and serum can also be sterilized without effect to their chemical constituents, and they remain perfectly safe for intravenous administration. Furthermore, toxoids and antitoxins can be rendered sterile without diminishing their potency. Enzyme solutions, penicillin and other anti-biotics can be treated according to this invention and rendered completely sterile.

We claim:

1. The process of sterilizing a solution of suspension without impairing potency or altering chemical or biologic activity which comprises subjecting it in a flowing film not over 3 mm. thick for a period of not more than 10 seconds to irradiation in which the energy between 2600 Å. and 2000 Å. is not less than 10 milliwatts per square centimeter and the energy below 2000 Å. is not less than 0.1 milliwatt per square centimeter.

2. The process of sterilizing a solution of sus-

pension without impairing potency or altering chemical or biologic activity which comprises subjecting it in a flowing film not over 1 millimeter thick for a period of not more than 1 second to irradiation in which the energy between 2600 Å. and 2000 Å. is not less than 10 milliwatts per square centimeter and the energy below 2000 Å. is not less than 0.1 milliwatt per square centimeter.

10 3. The process of sterilizing a solution or suspension without impairing potency or altering chemical or biologic activity which comprises subjecting it in a flowing film not over 3 mm. thick for a period of not more than 10 seconds to irradiation, in which the energy between 2600 Å. and 2000 Å. is not less than 1 milliwatt per square centimeter and the energy below 2000 Å. is not less than 0.1 milliwatt per square centimeter.

15 4. The process of sterilizing a solution or suspension without impairing potency or altering chemical or biologic activity which comprises subjecting it in a flowing film not over 1 mm. thick for a period of not more than 10 seconds to irradiation, in which the energy between 2600 Å. and 2000 Å. is not less than 1 milliwatt per square centimeter and the energy below 2000 Å. is not less than 0.1 milliwatt per square centimeter.

20 5. The process of sterilizing a solution or suspension without impairing potency or altering chemical or biologic activity which comprises subjecting it to a flowing film not over 3 millimeters thick for a period of not over 1 second to irradiation in which the energy between 2600 Å. and 2000 Å. is not less than 1 milliwatt per square centimeter and the energy below 2000 Å. is not less than 0.1 milliwatt per square centimeter.

25 6. The process of sterilizing a solution or suspension without impairing potency or altering chemical or biologic activity which comprises subjecting it in a flowing film not over 1 millimeter thick for a period of not over 10 seconds, to irradiation in which the energy between 2600 Å. and 2000 Å. is not less than 10 milliwatts per square centimeter and the energy below 2000 Å. is not less than 0.1 milliwatt per square centimeter.

30 7. The process of sterilizing a solution or suspension without impairing potency or altering chemical or biologic activity which comprises subjecting it in a flowing film not over 3 millimeters thick for a period of not more than 10 seconds to irradiation in which the energy below 2600 Å. is not less than 10 milliwatts per square centimeter.
